United States Patent Office.

ANDREW C. BLACK, OF KAUKAUNA, WISCONSIN.

Letters Patent No. 99,053, dated January 25, 1870; antedated January 16, 1870.

IMPROVEMENT IN MILKING-APPARATUS.

The Schedule referred to in these Letters Patent and making part of the same.

To all whom it may concern:

Be it known that I, ANDREW C. BLACK, of Kaukauna, in the county of Outagamie, and State of Wisconsin, have invented an Improved Milking-Apparatus; and I do hereby declare the following to be a full and correct description of the same, reference being had to the accompanying drawing, which represents a perspective view of the apparatus complete.

My invention consists in improvements in a combination milking-stool and pail-stand, and in uniting, with such improved apparatus, a clog or weight to be attached to the tail of the cow, to prevent those movements of it which would interfere with the cleanliness of the operation of milking, all as hereinafter set forth.

In the accompanying drawing—

A marks the body of the stool, on which the milker is to sit, and

B, the stand which supports the milking-pail.

To the top of the stool is attached, by the pivot *p*, and so as to swivel freely, the inclined turn-table C.

A similar turn-table, D, is attached, by pivot *p'*, to the top of the pail-stand B.

The object of these inclined turn-tables is to provide for the adjustment of the stool and stand, when on an uneven surface, so that the pail and the person of the milker will always rest upon a level or nearly level surface.

A ledge, *l*, prevents the pail from slipping off the table D.

Attached to the stool or stand, by a cord or chain, E, is the clog F, which is a heavy piece of wood, having the hooks G attached to it by the staples *s s*. This clog, which should be about five or six pounds in weight, is intended to be attached to the tail of the cow, by passing the hooks G into the tuft of hair at its lower end. When thus attached, the ordinary movements of the tail are prevented, and a cow, accustomed to be milked with the clog attached, soon ceases entirely to attempt them.

Having thus fully described my invention, What I claim, and desire to secure by Letters Patent, is—

A milking-stool, combining a stand for the milk-pail and a seat for the milker, each provided with an inclined turning-table, by which the level of the seat and of the pail may be maintained, when the stool rests upon an inclined or uneven surface, as set forth.

The above specification of my said invention, signed and witnessed at Washington, this 24th day of April, A. D. 1869.

ANDREW C. BLACK.
